US00D915917S

(12) **United States Design Patent** (10) **Patent No.:** **US D915,917 S**
(45) **Date of Patent:** **** Apr. 13, 2021**

(54) **SAFETY DEVICE FOR BREAK-IN PREVENTION**

(71) Applicant: **GeRoTech-Innovations GmbH**, Vienna (AT)

(72) Inventor: **Gerd Wolfinger**, Hagenbrunn (AT)

(73) Assignee: **GeRoTech-Innovations GmbH**, Vienna (AT)

(**) Term: **15 Years**

(21) Appl. No.: **29/687,846**

(22) Filed: **Apr. 16, 2019**

Related U.S. Application Data

(63) Continuation of application No. PCT/EP2017/076286, filed on Oct. 16, 2017.

(30) **Foreign Application Priority Data**

Oct. 17, 2016 (AT) ..... A 60001/2016
Feb. 9, 2017 (AT) ..... A 50106/2017
Apr. 8, 2019 (EM) 006372595

(51) **LOC (13) Cl.** **10-05**

(52) **U.S. Cl.** **USPC D10/106.7**
